UNITED STATES PATENT OFFICE.

VICTOR GAERTNER, OF NEW YORK, N. Y., ASSIGNOR TO CONTINENTAL SHEFFIELD SILVER CO., OF BROOKLYN, NEW YORK, A FIRM.

DESIGN FOR AN EAR FOR A HANDLE OF BOWLS OR SIMILAR ARTICLES.

56,230.

Specification for Design. Patented Aug. 31, 1920.

Application filed February 20, 1920. Serial No. 360,168. Term of patent 7 years.

To all whom it may concern:

Be it known that I, VICTOR GAERTNER, a citizen of the United States, residing at New York city, in the county and State of New York, have invented a new, original, and ornamental Design for an Ear for a Handle of Bowls or Similar Articles, of which the following is a specification, reference being had to the accompanying drawings, forming a part thereof, and in which—

Figure 1 is a side elevation;

Fig. 2 a plan view, and

Fig. 3 an edge view of an ear for a handle of bowls or similar articles embodying my design.

I claim:

The ornamental design for an ear for a handle of bowls or similar articles, as shown.

VICTOR GAERTNER.
